PRESSED SHEET METAL HOOK AND
METHOD OF FORMING SAME

Joseph O. Richard, Detroit, Mich.

Application January 26, 1942, Serial No. 428,296

6 Claims. (Cl. 29—150)

The invention relates to hooks designed for various uses such, for instance, as on truck bodies for securing the lacings which hold a covering fabric over the load.

It is an object of the invention to obtain a construction which can be formed from sheet metal or flat metal bars, without waste.

It is a further object to obtain a construction in which the return bent hook portion is laterally offset from the securing portion so as to permit easily fastening the latter to the body to which it is secured.

Still further, it is an object to reinforce the return bend of the hook and to fashion the same to a cross section which avoids any cutting edges in contact with the lacing.

With these and other objects in view, the invention consists:

First, in the peculiar construction of the sheet metal hook; and

Second, in the method of forming the same, as hereinafter set forth.

In the drawings:

Fig. 1 is a front elevation of the hook;

Fig. 2 is a side elevation thereof;

Fig. 3 is a cross section on line 3—3 of Fig. 2;

Fig. 4 is a plan view of the blank from which the hook is formed;

Fig. 5 illustrates the method and apparatus for offsetting a portion of the blank while maintained in the original plane thereof;

Fig. 6 is a cross section on line 6—6 of Fig. 5;

Fig. 7 illustrates the operation and apparatus for forming the return bend in the blank and simultaneously fashioning the cross sectional contour thereof;

Fig. 8 is a section on line 8—8 of Fig. 7; and

Fig. 9 illustrates the apparatus for further fashioning the cross sectional contour of the hook.

The blank from which the hook is formed may be cut without waste from sheet metal or a straight flat bar of metal. As illustrated in Fig. 4, the securing portion A of the hook is of the full width of the bar and during the blanking operation has apertures B, B' punched therein. The return bend portion C tapers from the portion A and is of lesser width so as to leave stock for the tapered end C' of another blank. Thus, all of the stock is used without waste, the two adjacent blanks being severed from each other along the line D.

The blanks thus formed are next fashioned to laterally offset the portion C from the portion A while said portions are in the same plane.

This may be accomplished by complementary grooved dies E, E', as illustrated in Figs. 5 and 6.

The next step is to form the return bend, the center of which is substantially on line 6—6 of the offset blank. This operation is performed by a female die G and a cooperating male die H, these being fashioned to a concavo-convex cross sectional contour, as illustrated at I in Fig. 8. The hook is then placed between dies J and K, which laterally contract the concavo-convex cross section to form a hollow reinforcing rib L. Finally, the free end portion M of the hook is pressed inward to contract the opening which, however, has a slightly flaring portion.

A hook formed as above described may be easily secured to the body to which it is attached, inasmuch as the apertures B, B' for receiving the fastening bolts are offset from the return bent portion C.

The cross section of this return bend is as shown in Fig. 3, the hollow reinforcing rib adding a high degree of rigidity to the hook.

Also, as this rib extends inward with respect to the return bend, it forms a rounded bearing for engagement with the rope or lacing, thereby avoiding any cutting edge.

What I claim as my invention is:

1. A pressed sheet metal hook comprising a flat securing portion apertured for engagement of fasteners, and a tapering return bend portion laterally offset with respect to said securing portion not to obstruct the apertures therein, said return bend portion being of a concavo-convex cross sectional contour forming a hollow reinforcing rib extending around the bend and projecting radially inwardly thereof and the length of the return portion being nearly equal to that of the securing portion.

2. A pressed sheet metal hook comprising a flat securing portion apertured for engagement with the fastening means, a tapering return bend portion laterally offset to one side of the apertures in said apertured portion to avoid obstructing the same and being of concavo-convex cross sectional contour to form a reinforcing rib extending around the return bend, the length of the return portion being nearly equal to that of the securing portion.

3. The method of forming pressed sheet metal hooks comprising cutting a flat strip having parallel edges along a generally oblique line to form thereof without waste similar complementary blanks, each having a substantially rectangular securing portion the full width of the strip and a portion extending therefrom of lesser width and tapering toward its outer end, bending each of

said blanks in the plane thereof and in an intermediate sub-portion of said tapering portion to laterally offset an end sub-portion of said tapering portion from the securing portion, and forming a return bend in said intermediate sub-portion and also fashioning the cross sectional contour thereof concavo-convex, thereby forming a hollow reinforcing rib extending around the bend.

4. The method of forming pressed sheet metal hooks comprising cutting a sheet metal blank with a substantially rectangular securing portion and a tapering portion extending from one end thereof and simultaneously forming fastener apertures in said securing portion, bending an intermediate sub-portion of said tapering portion of said blank in the plane thereof to laterally offset an end sub-portion of said tapering portion from the rectangular securing portion so as to be at one side of the apertures therein, and forming a return bend in said tapering portion and also fashioning the cross sectional contour thereof concavo-convex, thereby forming a hollow reinforcing rib extending around the bend on the inner side thereof.

5. The method of forming pressed sheet metal hooks comprising cutting a sheet metal blank with a substantially rectangular securing portion and a tapering portion extending from one end thereof and simultaneously forming fastener

apertures therein, bending an intermediate sub-portion of said tapering portion of said blank in the plane thereof to laterally offset an end sub-portion of said tapering portion so as to be at one side of the apertures therein from the securing portion, forming a return bend in said tapering portion with an outwardly flaring free end portion and also fashioning the cross sectional contour thereof concavo-convex to form a hollow reinforcing rib extending around the bend on the inner side thereof, and further bending inward the return portion intermediate the bend and its free end, the latter being outwardly flared.

6. The method of forming pressed sheet metal hooks comprising forming a sheet metal blank with a substantially rectangular securing portion and a tapering portion extending from one end thereof, placing said blank in dies which hold it in its plane, relatively moving said dies to bend an intermediate sub-portion of said tapering portion and to laterally offset an end sub-portion of the latter from said securing portion, forming a return bend in said intermediate sub-portion and in a plane transverse to the plane of the blank, also fashioning the cross sectional contour of said return bend concavo-convex to form a hollow reinforcing rib, and further bending inward the end sub-portion of said tapering portion with an outward flare at its end.
